UNITED STATES PATENT OFFICE.

CHARLES BELKNAP, OF BURLINGTON, WASHINGTON.

BRICKLAYER'S JOINTER.

Application filed April 21, 1925. Serial No. 24,718.

To all whom it may concern:

Be it known that I, CHARLES BELKNAP, a citizen of the United States, residing at Burlington, in the county of Skagit and State of Washington, have invented a new and useful Bricklayer's Jointer; and I do hereby declare that the following is a full, clear, and exact specification, such as will enable others skilled in the art to which it appertains to make and use the same.

The invention is a device for enabling a bricklayer to rake mortar from the joint between bricks and thereby smooth or "strike the joint."

15 The object of the invention is to provide a simple and efficient device for enabling bricklayers to rake or "strike the joint" between bricks or the like.

20 Another object of the invention is to provide a tool of the class described which is provided with double shoes so that any mortar left by one shoe will be removed by the other.

25 And a further object of the invention is to provide a tool for bricklayers which is of a simple and economical construction.

With these ends in view the invention embodies a tool having two shoes, one in line with other or following the other and a handle which is constructed so that it will limit the distance the shoes may pass into a joint.

30 Other features and advantages of the invention will appear from the following description taken in connection with the drawings, wherein:

Figure 1 is a side elevation of the tool.

Figure 2 is a plan view.

In the drawings I have shown my device as it would be constructed wherein numeral 1 indicates the handle, numeral 2 the forward shoe and numeral 3 the rear or following shoe.

45 The entire tool is made of a single bar with the ends bent to form the shoes, then bent vertically to form sections 4 and 5, then bent outwardly to form sections 6 and 7, and then bent rearwardly to form the bars 8 and 9 which form the handle and which are provided with a flattened loop 10 to provide a small amount of spring between the members. The bars 8 and 9 are also bent upward at the point 11 as shown in Figure 1.

It will be observed that the shoe 2 is curved and beveled at the point 12 and the shoe 3 is curved and beveled at the point 13 which is on the opposite side to that of the point 12 on the shoe 2. This will provide means for locating the device in the joint as the beveled surface 12 will strike the edge of the joint if the device is placed against this side of the joint and the beveled surface 13 will engage the opposite side if the device is placed against the opposite side.

It will be understood that changes may be made in the construction without departing from the spirit of the invention, one of which changes may be in the use of material of any other suitable shape or design, another may be in the design of the handle and still another may be in the varying of the distance between the bottoms of the shoe and the bottoms of the bars 8 and 9 so that the depth that the shoes will penetrate the joint may be varied.

The construction may be readily understood from the foregoing description. To use the device, the handle may be held in the right hand and the shoes may be placed at the far side of the joint and pulled toward the person using the device. It will be observed that the first shoe comes into contact with the brick on one side of the joint, thereby cleaning away the mortar that falls and the mortar that is left will be caught by the second shoe which will engage the brick on the opposite side, thereby providing a clean, smooth joint.

Having thus fully described the invention what I claim as new and desire to secure by Letters Patent is:

1. In a tool of the class described two rectangular shaped shoes arranged so that one follows the other, each of said shoes having beveled toes and one of said toes being curved on one corner and the other on the opposite corner, a handle for supporting the said shoes and means on said handle for limiting the distance the said shoes may extend into a groove or the like.

2. In a bricklayer's jointer, two shoes formed of rectangular shaped bars with beveled toes, and one of said toes curved on one side and the other on the opposite side, vertical posts extending upward from the heel of the said shoes, horizontal bars ex-

tending outward from the tops of the posts, then backward to a common point and in a line parallel to the base of the shoes and then angularly upward to form a handle, and said bars being joined with a spring loop at the upper end of the handle.

3. In a jointer of the class described a pair of shoes formed of rectangular shaped bars

with beveled toes curved at their opposite corner, a handle, and means for connecting the shoes to the handle, said connecting means forming a stop to limit the distance the shoes may extend into a groove or the like.

CHARLES BELKNAP.
